UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

UPPER-FORMING MACHINE.

1,425,503.

Specification of Letters Patent. Patented Aug. 15, 1922.

Application filed May 19, 1920. Serial No. 382,530.

To all whom it may concern:

Be it known that I, ARTHUR BATES, a subject of the King of England, residing at Leicester, Leicestershire, England, have invented certain Improvements in Upper-Forming Machines, of which the following description, in connection with the accompanying drawings, is a specification, like reference characters on the drawings indicating like parts in the several figures.

This invention relates to machines for forming or shaping uppers in the manufacture of boots and shoes. The invention is applicable to the forming or shaping of assembled upper materials including, for example, the upper leather, the lining, and an end stiffener or counter, or to the forming of one or more of such materials, for example the stiffener alone, and the term "upper" is accordingly used herein as referring generally to one or more of such materials. In many of its aspects the invention relates more particularly to means for forming an end portion of an upper, and is herein illustrated in its application to means for shaping the heel end portion of an upper, although in general the invention is not limited to heel end forming means but is likewise applicable to toe forming operations.

A feature of the invention consists in novel means for shaping an upper on a form, which may or may not be the shoe last, to produce on the margin of the upper a flange extending at an angle to the bottom face of the form and located at a distance from the edge of said face. For the purpose of forming or molding the heel end portion of an upper before the parts of the shoe are assembled on a last, the illustrative machine comprises a metal heel end form on which the upper is shaped as above set forth, the invention thus having in contemplation the manufacture of a type of shoe in which the upper is secured to the insole by sewing it to a rib which extends round the heel end as well as along other portions of the insole. To assist in the flange forming operation the invention, in its illustrative embodiment, provides margin holding members constructed and arranged to extend along the inner surface of the margin of the upper round the end of the form and to co-operate with inwardly movable upper shaping or bending

means, for example end embracing wipers, to hold the margin of the upper against the edges of the wipers in such manner as to distribute the fullness and to avoid the formation of large pleats or folds as the margin is gathered and wiped inwardly, these members being mounted for movement together lengthwise of the form and for relative movement laterally of the form in response to the pressure of the advancing and closing wipers and limited as to such movements to cause them to serve as abutments against which the margin is finally shaped to produce a flange "upstanding" relatively to the bottom face of the form.

Features of the invention are also to be recognized in novel means adapted for use to secure different results in the upper forming operation, the construction shown comprising means whereby a variation may be effected in the distance from the edge of the bottom face of the form at which the upstanding flange is located, and whereby also the machine is adapted for use either to produce an upstanding flange as above set forth or to produce a flange extending throughout its width in substantially parallel relation to the bottom face of the form. In the construction shown these results may be secured by adjustment of means whereby the movements of the margin holding members lengthwise and laterally of the form are limited, together with corresponding adjustment of the wiper movements, the illustrative construction comprising stops which are separately adjustable to limit respectively the movement of the members lengthwise of the form and their movements laterally of the form. By the use of such independently adjustable stops, moreover, a variation may be effected in the relative pressures with which the margin of the upper is molded between the holding members and the wipers at the end and the sides of the form respectively, which is an additional advantageous characteristic of the novel construction provided.

Still another feature of the invention consists in novel means for preventing outward return movement of the margin holding means from any position to which it is moved in the flange forming operation, thus avoiding displacement of the flange while permitting, for example, a plurality of re-

ciprocatory movements of the wipers following their first advancing and closing movement.

The above and other features of the invention, including certain details of construction and combinations of parts, will now be described with reference to the accompanying drawings and pointed out in the claims.

10 In the drawings:

Fig. 1 is a view in side elevation of a machine in which the invention is embodied;

Fig. 2 is a perspective view showing the heel end form and parts associated therewith in the upper forming operation;

Fig. 3 is a perspective view of parts shown in Fig. 2, together with a portion of the flange forming wipers, as the parts appear at the beginning of the flange forming operation;

Fig. 4 is a view similar to Fig. 3 showing the parts as they appear at the end of an inward flange forming movement of the wipers when the parts are adjusted to produce an upstanding flange on the margin of the upper, and

Fig. 5 is a detail view illustrating more fully the arrangement of means for variably limiting the movements of the margin holding members.

For purposes of illustration the invention is shown as applied to a type of upper forming machine illustrated and described in United States Letters Patent No. 1,197,439, granted on September 5, 1916 upon an application of Matthias Brock, and more fully also as to certain features in other prior patents of Matthias Brock, No. 1,361,960 granted on December 14, 1920 and No. 40 1,376,388 granted on April 26, 1921. Features of the general organization of the machine, in so far as they have not been modified for the purposes of the present invention, will therefore be described only briefly, 45 and for a more complete understanding of the organization of the machine and the details of construction reference may be made to said prior patents.

The machine comprises a heel end form 2 which is supported on a form carrier 4 mounted for movement on the frame of the machine from a starting position indicated in Fig. 1 to carry the member 2 and the upper into a multi-part outside former or form embracing mold indicated by dotted lines at 6 in Fig. 1, the form 2 being mounted on the upper end of a two-part plunger 8 vertically movable in the carrier 4 and between the parts of which is a compression spring 10. Power is derived from a pulley 12 on a shaft 14 whereby through gearing, and under control of a clutch 16, movement is imparted to a cam shaft 18 provided with a plurality of cams, not shown 65 in detail, for operating various parts of the

machine. When the clutch 16 is actuated by depression of a starting treadle 20, movement is imparted from a cam on the shaft 18 to a lever 22 which operates through a link 24 connected to the carrier 4 to move the carrier toward the right (Fig. 1) to carry the form 2 into the outside former and to maintain it in such position during subsequent operations of the machine. Similarly to prior machines, the machine shown has 75 also means for imparting upward movement yieldingly to the form member 2, comprising a toggle 26, a plunger 28, a lever 30 and a link 32, and also means for closing the outside former about the form 2, comprising a 80 toggle 34, a link 36 and a lever 38.

After the upper has been securely clamped between the form 2 and the outside former 6, the margin of the upper which projects upwardly above the heel seat face of the 85 form is gathered and bent inwardly over said face by the action of bending means comprising wipers which, as in prior constructions, may comprise end wiper members 40 (Fig. 4) mounted for advancing 90 and closing movements and side wiper members 42 which close inward laterally of the form without advancing. Operative movements are imparted to these wipers by independently operated power means comprising 95 a pulley 44 arranged to be connected through clutch mechanism to reciprocable wiper connections consisting of a pitman 46 and a wiper connected rod 48. The wiper clutch is controlled by a lever 50 arranged 100 to be engaged and operated by a plate 52 to start the operation of the wipers upon downward movement of a plate supporting rod 54 operated by a cam on the shaft 18 through a lever 56. Clutch tripping movement is imparted to this rod after the upper has been clamped as above described, whereupon the cam shaft 18 comes automatically to rest. A plurality of reciprocatory movements inwardly and outwardly over the heel 105 seat face of the form are then imparted to the wipers until such time as the operator again depresses the treadle 20, whereupon the wiper clutch is actuated to stop the movement of the wipers and the various parts of 110 the machine are returned to starting position. In the construction shown, as in prior machines, there is provision for lost motion between the pitman 46 and the rod 48 to avoid completely withdrawing the wipers 115 from over the heel seat face of the form until their final retractive movement, such lost motion resulting from relative sliding movement between the rod 48 and a bearing member 58 to which the pitman 46 is 120 connected, within limits determined by a collar 60 clamped on the rod 48 and nuts 62 on the end of the rod. By adjustment of the collar 60 and the nuts 62, combined preferably with a compensating adjustment of 125 130

the wiper plates as explained in Patent No. 1,376,388, the starting position of the wipers may be varied, resulting in a variation in the limit of advancing and closing movement of the wipers over the heel seat face of the form. The parts as thus far described may be constructed and arranged as more fully shown and described in said prior patents.

- 10 To increase the effectiveness of the wipers in their hold on the margin of the upper, and to avoid the formation of large pleats or folds as the margin is gathered and wiped inwardly, the machine, similarly to the machine of Patent No. 1,361,960, is provided with a pair of margin holding members 64 which are curved in substantial conformity to the curve of the edges of the wipers and are relatively movable laterally of the form 20 about a pivot 66 fast on a foot piece or holder 68 mounted to slide in a dovetailed guideway extending lengthwise of the form member 2. The outer ends of the members 64 are connected by toggle links 70 to a block 72 which is guided in the holder 68. Extending from the block 72 is a rod or stem 74 the outer end of which is engaged by a presser arm 76 fast on a rock shaft 78 on the form carrier 4. Fast also on the shaft 78 is a substantially horizontal arm 80 arranged to be pressed downwardly by means of a spring 82, thereby causing the arm 76 to press the stem 74 and the members 64 normally toward the rear end of the form as far as permitted by engagement of the holders 68 with the form at the end of its slot, the arm 76 also acting through the toggle links 70 to spread the members 64 laterally of the form, assisted by the action of light leaf springs 84.
- 35 The members 64 are thus maintained initially with their outer upper engaging faces at or near the edge of the heel seat face of the form round its rear end in position to clamp the upstanding margin of the upper 40 against the edges of the wipers as the latter are advanced and closed, the margin holding members yielding both lengthwise and laterally of the form against the pressure of the arm 76 throughout the advancing and closing movement of the wipers.
- 45 It is desirable in an organization such as herein shown, in which repeated wiper movements are effected, to prevent, after the first advance of the wipers, outward return movement of the members 64 in such manner as to displace the flange of the upper or to interfere with the subsequent action of the wipers. For this purpose there is provided in the outer end of the arm 80 a spring held 50 pin or catch 86 arranged, in accordance with the present invention, to co-operate with a series of ratchet teeth on a ratchet segment 88 into operative relation to which the pin is carried by the inward movement of the form carrier 4. In the first advance of the wipers

the pin 86 is moved upwardly along the series of ratchet teeth which are effective in any position to which the members 64 are moved to relieve them of the pressure of the spring 82 and thus prevent them from returning outwardly over the form as the wipers are retracted. It will be understood that the tension of the leaf springs 84 is sufficiently light to prevent any such lateral outward pressure of the members 64 against the flange of the upper as would damage or displace the flange or interfere with the subsequent action of the wipers.

Further, for purposes of the present invention, there is mounted in a plate 90 fast on the form 2 a stop screw 92 for engagement with an upstanding lug 94 on the holder 68 to limit inward movement of the members 64 lengthwise of the form, this screw being adjustable to determine different limits of movement of the members as may be required. For limiting also swinging movement of the members 64 laterally of the form, the machine is provided with a stop nut 96 threaded on the stem 74 and arranged to engage the lug 94. By adjustment of the stop members 92 and 96 such limits of movement of the members 64 lengthwise and laterally of the form may be determined as to cause these members to act as abutments against which the wipers may finally mold the margin of the upper, in such manner as to produce at a predetermined distance from the edge of the heel seat face of the form an upstanding flange on the margin of the upper, as illustrated in Fig. 4, which may be used subsequently in sewing the upper to a rib on an insole. It will be evident that the adjustable stops 92 and 96 permit a variation in the distance from the edge of the form at which the upstanding flange is produced, and that through the provision for independent adjustments of the different stops a variation may be effected, if desired, in the relative pressures with which the upstanding margin of the upper is molded at the end and the sides of the form respectively. On the other hand, if the machine is to operate on work in which the inturned flange on the margin of the upper is to lie flat upon the heel seat throughout its width, the stops 92 and 96 may be adjusted in such manner as to permit the members 64 to be forced farther inwardly over the form, permitting the wipers to wipe the margin of the upper completely down upon the heel seat face. It will be understood that adjustment of the stops to adapt the machine for different kinds of work will be accompanied by corresponding adjustments to vary the distance which the wipers are advanced and closed over the form, as hereinbefore explained.

Since the manner in which the different parts of the machine operate to perform their functions and the sequence of the op-

erations as a whole have been set forth in connection with the detailed description of the machine, no further description of the operation is necessary for an understanding 5 of the invention.

Having described the invention, what I claim as new and desire to secure by Letters Patent of the United States is:

1. In a machine for shaping an upper 10 over a shoe form, co-operating members arranged to engage the margin of the upper respectively on its outer and inner faces round an end of the form and movable lengthwise and laterally of the form with 15 the margin of the upper so held between them as to permit it to slip as the members move inwardly, and controlling mechanism to cause said members after a determinate movement inwardly over the form to mold 20 a portion of the margin between them to produce a flange at an angle to the bottom face of the form.

2. In a machine for shaping an upper 25 over a shoe form, co-operating devices arranged to engage the margin of the upper respectively on its outer and inner faces round an end of the form and movable lengthwise and laterally of the form with the margin of the upper so held between 30 them as to permit it to slip as said devices move inwardly, and means operative after a determinate movement of said devices over the form to resist further movement of the inner device lengthwise and laterally of the 35 form to cause it to serve as an abutment in co-operation with the outer device to mold a portion of the margin of the upper into a flange extending at an angle to the bottom face of the form.

3. In a machine for shaping an upper 40 over a shoe form, the combination with upper shaping means movable inwardly over the bottom face of said form round an end of the form in engagement with the outer surface of the margin of the upper to bend the margin inwardly over said face, of means for engaging the margin of the upper on its inner surface to hold it against said upper shaping means in upstanding relation to the bottom face of the form, said margin holding means being movable lengthwise and laterally of the form as said upper shaping means moves inwardly, and mechanism for limiting movement of said 55 margin holding means to cause it to serve as an abutment in co-operation with said upper shaping means to produce on a portion of the margin of the upper a flange extending at an angle to the bottom face of the form.

4. In a machine for shaping an upper 60 over a shoe form, the combination with upper shaping means movable lengthwise and laterally of the form to bend the margin of the upper inwardly over the bottom face of the form, of a device arranged to

engage the inner surface of the margin of the upper to hold it against said upper shaping means comprising members movable together lengthwise of the form and relatively movable also laterally of the form in response to pressure of said upper shaping means, and means for limiting the lengthwise and lateral movements of said members to cause them to serve as abutments in co-operation with said upper shaping means to produce on the margin of the upper a flange extending at an angle to the bottom face of the form.

5. In a machine of the class described, the combination with a shoe form, of end embracing wipers movable to gather and wipe the margin of an upper inwardly over the bottom face of said form, members arranged to engage the inner surface of the margin of the upper along and in front of the edges 80 of the wipers and mounted for movements lengthwise and laterally of the form in response to pressure of the wipers, and means for limiting the movements of said members to cause them to serve as abutments 85 in co-operation with the wipers to produce on a portion of the margin of the upper a flange at an angle to the bottom face of the form.

6. In a machine of the class described, the combination with a shoe form, of end embracing wipers movable to gather and wipe the margin of an upper inwardly over the bottom face of said form, members arranged to engage the inner surface of the 95 margin of the upper along and in front of the edges of the wipers and mounted for movements lengthwise and laterally of the form in response to pressure of the wipers, means yieldingly opposing said movements 100 of the members, and stops for limiting respectively the movements of said members lengthwise and laterally of the form to cause them to serve as abutments in co-operation with the wipers to produce on the margin 110 of the upper a flange at an angle to the bottom face of the form.

7. In a machine of the class described, the combination with a shoe form, of means for shaping the margin of an upper over the 115 bottom face of said form to produce a molded flange extending at an angle to said face at a distance from the edge of said face, said upper shaping means being adjustable to vary the distance from the edge of said 120 face at which said flange is located.

8. In a machine for shaping an upper 125 over a shoe form, members for engaging the margin of the upper respectively on its outer and inner faces and movable inwardly over the bottom face of the form to flange the margin of the upper, and means for limiting the inward movement of the inner member to cause it to serve as an abutment in co-operation with the outer member to pro- 130

duce on the margin of the upper a flange at an angle to the bottom face of the form, said limiting means being adjustable to vary the distance from the edge of the bottom 5 face of the form at which said flange is located.

9. In a machine for shaping an upper over a shoe form, the combination with upper shaping means movable inwardly over the 10 bottom face of said form in engagement with the outer surface of the margin of the upper to bend the margin inwardly over said face, of means for engaging the margin of the upper on its inner surface 15 to hold it against said upper shaping means in upstanding relation to the bottom face of the form, said margin holding means being movable lengthwise and laterally of the form as said upper shaping means moves 20 inwardly, and means for limiting movements of said margin holding means lengthwise and laterally of the form to cause said means to serve as an abutment in co-operation with said upper shaping means to produce 25 on a portion of the margin of the upper a flange extending at an angle to the bottom face of the form, said limiting means being adjustable to vary the distance from the edge of the bottom face of the form at 30 which said flange is produced.

10. In a machine for shaping an upper over a shoe form, the combination with means for gathering and wiping the margin of the upper inwardly over the bottom 35 face of the form round an end of the form, of members arranged to engage the inner surface of the margin of the upper round an end of the form and yieldingly movable lengthwise and laterally of the form 40 in response to pressure of said wiping means, and means for limiting the movements of said members to cause them to serve as abutments in co-operation with the wiping means for molding a portion of the 45 margin of the upper into a flange extending at an angle to the bottom face of the form, said limiting means being adjustable to vary the distance from the edge of the bottom face of the form at which said 50 flange is located.

11. In a machine for shaping an upper over a shoe form, the combination with upper shaping means movable inwardly over the bottom face of said form round 55 an end of the form in engagement with the outer surface of the margin of the upper to bend the margin inwardly over said face, of means for engaging the margin of the upper on its inner surface to hold it against 60 said upper shaping means, said margin holding means being movable lengthwise and laterally of the form in response to pressure of said upper shaping means, and means for limiting movements of said margin holding means lengthwise and laterally 65

of the form to cause said means to serve as an abutment in co-operation with said upper shaping means to mold a portion of the margin of the upper into a flange extending at an angle to the bottom face of 70 the form, said limiting means being adjustable to produce a relative variation in the molding pressures as between the end and the sides of the end portion of the upper. 75

12. In a machine of the class described, the combination with a shoe form, of end embracing wipers for gathering and wiping the margin of an upper inwardly over the bottom face of said form, members arranged to engage the inner surface of the margin of the upper along the edges of said wipers and yieldingly movable lengthwise and laterally of the form in response to pressure of the wipers, and means for 80 limiting the movements of said members to cause them to serve as abutments in co-operation with the wipers to produce on a portion of the margin of the upper a flange at an angle to the bottom face of the 85 form, said limiting means being adjustable to produce a relative variation in the limits of movement of the members lengthwise and laterally of the form. 90

13. In a machine of the class described, 95 the combination with a shoe form, of end embracing wipers for gathering and wiping the margin of an upper inwardly over the bottom face of the form, members arranged to engage the inner surface of the margin of the upper along the edges of said wipers and yieldingly movable lengthwise and laterally of the form in response to pressure of the wipers, and stops for 100 limiting respectively the movements of said members lengthwise and laterally of the form, said stops being adjustable each independently of the other to vary the 105 limits of movement of the members in the different directions. 110

14. In a machine of the class described, the combination with a shoe form, of means for gathering and wiping the margin of an upper inwardly over the bottom face of said form round an end of the form, members arranged to engage the inner surface of the margin of the upper round the end of the form, a holder on which said members are mounted for relative movements laterally of the form, said holder being 115 mounted for movement to carry the members bodily lengthwise of the form, a stop for limiting adjustably said movement of the holder, and mechanism comprising an additional stop for limiting adjustably the 120 movements of the members laterally of the form. 125

15. In a machine of the class described, the combination with a shoe form, of means for gathering and wiping the margin of an 130

upper inwardly over the bottom face of said form round an end of the form, members arranged to engage the inner surface of the margin of the upper round the end of the 5 form, a holder on which said members are mounted for relative movements laterally of the form, said holder being mounted for movement to carry the members bodily lengthwise of the form, a stop for limiting 10 adjustably said movement of the holder, toggle links connected to said members, a rod extending from said toggle links, and a stop adjustable on said rod and arranged to engage a portion of said holder to limit 15 relative movements of said members laterally of the form.

16. In a machine of the class described, the combination with a shoe form, of means for molding the margin of an upper over 20 the bottom face of said form, said molding means being adapted for alternative use to mold the margin throughout its width in parallel relation to said face or to produce on a portion of said margin a flange extending 25 at an angle to said face.

17. In a machine of the class described, the combination with a shoe form, of means for flanging the margin of an upper over the bottom face of said form comprising 30 members movable inwardly over said face with the margin so held between them as to permit it to slip as the members move inwardly, and means for varying the limit of movement of said members for producing 35 on a portion of the margin a flange extending at an angle to the bottom face of the form or alternatively for stripping the margin of the upper completely out from between said members and shaping it through 40 out its width in parallel relation to said face.

18. In a machine of the class described, the combination with a shoe form, of means for bending the margin of an upper inwardly over the bottom face of said form, a margin holding device arranged to engage the margin of the upper on its inner surface and movable inwardly in response to the pressure of said bending means, and 45 means for limiting the inward movement of said device to cause it to serve as an abutment in co-operation with the bending means for producing on a portion of the margin of the upper a flange at an angle 50 to the bottom face of the form, said limiting means being movable alternatively to permit the margin of the upper to be shaped throughout its width in parallel relation to said face.

55. 19. In a machine of the class described, the combination with a shoe form, of end embracing wipers for gathering and wiping the margin of an upper inwardly over the bottom face of said form, members arranged 60 to engage the inner surface of the margin

of the upper along the edges of said wipers and yieldingly movable lengthwise and laterally of the form in response to the pressure of the wipers, and means for limiting the movements of said members to cause 70 them to serve as abutments in co-operation with the wipers for producing on the margin of the upper a flange extending at an angle to the bottom face of the form, said limiting means being adjustable to permit 75 the members to be moved farther inwardly in response to pressure of the wipers for wiping the margin throughout its width into parallel relation to the bottom face of the form.

20. In a machine for shaping an upper over a shoe form, the combination with upper shaping means movable inwardly over the bottom face of said form round an end of the form in engagement with the outer 85 surface of the margin of the upper to bend the margin inwardly over said face, of means arranged to engage the margin of the upper on its inner surface round the end of the form to hold it against said upper shaping means and mounted for movement inwardly over the bottom face of the form in response to the pressure of said upper shaping means, means yieldingly opposing the inward movement of said margin 95 holding means, and mechanism automatically operative to prevent outward return movement of said margin holding means with said upper shaping means from any position to which it is moved by the upper 100 shaping means.

21. In a machine of the class described, the combination with a shoe form, of end embracing wipers movable to gather and wipe the margin of an upper inwardly over 105 the bottom face of said form, margin holding means arranged to engage the margin of the upper on its inner surface and to be moved inwardly over the bottom face of the form by said wipers, spring means 110 against the tension of which said margin holding means is movable inwardly, means for limiting and for varying the limit of inward movement of said margin holding means, and mechanism automatically operative 115 to prevent outward return movement of said margin holding means during return movement of the wipers irrespective of the limit of movement of said holding means.

22. In a machine of the class described, the combination with a shoe form, of means movable inwardly over the bottom face of said form to bend the margin of an upper over said face, a device arranged to engage 125 the margin of the upper on its inner surface to hold it against said bending means and to be moved inwardly over the bottom face of the form by said bending means, spring means against the tension of which 130

said margin holding device is movable inwardly, and mechanism comprising a ratchet-toothed member and a co-operating catch to prevent outward return movement of said device from any position to which it is moved by said bending means.

23. In a machine of the class described, the combination with a shoe form, of means for bending the margin of an upper inwardly over the bottom face of said form, a margin holding device arranged to engage the margin of the upper on its inner surface and movable inwardly in response to the pressure of said bending means, spring means against the tension of which said device is movable inwardly, means for limiting the inward movement of said device to

cause it to serve as an abutment in co-operation with the bending means for molding a portion of the margin of the upper into a flange extending at an angle to the bottom face of the form, said limiting means being movable alternatively to permit the margin of the upper to be shaped throughout its width in parallel relation to said face by the bending means, and mechanism automatically operative to prevent outward return movement of said margin holding device from any position to which it is moved by the bending means.

30 In testimony whereof I have signed my name to this specification.

ARTHUR BATES.
